UNITED STATES PATENT OFFICE.

JOHN FESTA, OF BROOKLYN, NEW YORK.

GAS-BURNER.

1,394,721.

Specification of Letters Patent. Patented Oct. 25, 1921.

Application filed April 27, 1920. Serial No. 376,997.

To all whom it may concern:

Be it known that I, JOHN FESTA, a citizen of the United States, and residing at Brooklyn, Kings county, and New York State, have invented certain new and useful Improvements in Gas-Burners, of which the following is a specification.

This invention relates to gas burners and more especially to burners used in heaters and its object is to provide a mixing chamber with outlet nipples divided at their orifices and extending upward from the chamber so that danger of back fire is eliminated and the flame is divided to permit of the 15 consumption of more oxygen while the mixed vapor is evenly distributed to each nipple, as will be more fully described and the details enumerated in the following specification and set forth in the appended 20 claims, and the device illustrated in the accompanying drawings, wherein:

Figure 1 is an elevation of the improved burner.

Fig. 2 is a vertical longitudinal sectional 25 view of the same,

Fig. 3 is a plan view of the burner,

Fig. 4 is a cross sectional view on the line 4—4 of Fig. 2.

A serious objection to the burners commonly used in gas heaters is the danger of back fire in consequence of the proximity of the nipple to the gas inlet nozzle and the lack of air supply to all the gas jets often results in ineffectual combustion and waste 35 of gas.

To overcome these failures in burners as heretofore constructed, the mixing chamber of the device shown in the drawings is divided into two compartments 5 and 6, the 40 latter receiving its supply of air and gas through the pipe 7, and from the inlet 8 and nozzle 9, of the supply pipe 10, to which may be secured suitable piping from the desired source. The nipple 9, is threaded 45 and playing in the same, is the shield 11, that may be advanced toward the open end of the inlet 8, sufficiently to regulate the supply of air and be secured to any adjustment by the screw 12.

50 The air and gas on leaving the pipe 7, are thoroughly mixed in compartments 5 and 6, by striking the partition 13, being deflected laterally and passing through the openings 14, where on entering compartments 5, 55 it is diffused to right and left as its force is

spent against the upper wall 15, and between two of the nipples 16, at each side.

This arrangement of the mixing chambers insures a perfect distribution of the mixed vapor to the nipples and where an identical volume of gas is furnished to each outlet. This can only be attained by supplying the vapor at a central point and not from one end and where the jets will decrease in size toward the other end of the 60 burner and where the supply for the last nipple is so weak that it will not remain lighted but allow the escape of the gas to the room in which the burner is located.

The nipples 16 are made of short sections of pipe, threaded and screwed into holes that are tapped in the wall 15. Across the upper end is fitted a partition 17, of thin sheet metal and this end is compressed and flattened so that there is an orifice for the 70 escape of vapor on each side of the partition, thus providing for two parallel flames with space between them for the admission of air on both sides and it is evident that by closing the orifices will provide a flame of 75 greater expansion and more adaptable for heaters where reflection surfaces are used.

It will be seen that with a burner constructed as above described and illustrated, it will be practically impossible for a flame 80 to descend through the nipples, the two compartments 5 and 6, and the pipe 7, to the nozzle 9 and fire the gas and supply at that point. It is also evident that the gas and air are evenly and thoroughly mixed in passing 85 from the inlet pipe 7 to the nozzles by the arrangement of the compartments 5 and 6, and that the size of the jets is readily regulated by degree to which the nipples are compressed at their outlets.

Obviously the parts may be otherwise arranged and modified without departing from the essential features above described or from the scope of the appended claim.

What I claim as new is:—

In a gas burner, the combination of a horizontal cylindrical pipe having openings along its upper side and closed at its ends, a mixing chamber integral with the said pipe and having at its separate ends a 100 communicating opening, a vapor supply pipe beneath the mixing chamber and parallel with the same and the horizontal cylindrical pipe, nipples for the openings in the latter pipe and having slotted orifices in line with 105

100

100

110

and parallel with said horizontal cylindrical pipe, and a dividing plate in each slot adapted to divide the flame so that the nipples will supply two separate and distinct 5 and continuous flames along the pipes and mixing chamber.

In testimony whereof, I have signed my

name to this specification in the presence of two subscribing witnesses, this 20th day of April, 1920.

JOHN FESTA
